CLAIM

The ornamental design for a cutting insert, as shown and described.

DESCRIPTION

FIG. 1 is a front view of a cutting insert

FIG. 2 is a rear view thereof;

FIG. 3 is a top view thereof;

FIG. 4 is a bottom view thereof;

FIG. 5 is a right side view thereof;

FIG. 6 is a left side view thereof;

FIG. 7 is a first perspective view thereof;

FIG. 8 is a second perspective view thereof;

FIG. 9 is a cross sectional view taken along line 9-9 of FIG. 3;

FIG. 10 is a cross sectional view taken along line 10-10 of FIG. 3;

FIG. 11 is a cross sectional view taken along line 11-11 of FIG. 3;

FIG. 12 is a cross sectional view taken along line 12-12 of FIG. 3;

FIG. 13 is a cross sectional view taken along line 13-13 of FIG. 3;

(Continued)

FIG. 14 is a cross sectional view taken along line 14-14 of FIG. 1; and,

FIG. 15 is a referential perspective view showing the state in use of the cutting insert attached to the holder by a fixing member, for cutting a workpiece.

The broken lines in the referential perspective view depict unclaimed environmental subject matter.
